UNITED STATES PATENT OFFICE.

CHARLES E. SHIVELY, OF PORTSMOUTH, OHIO.

SHOE RACK.

Application filed July 11, 1928. Serial No. 291,754.

This invention relates to racks for conveying shoes in a factory.

An object of the invention is the provision of a simple, compact and efficient device for supporting and conveying shoes in any formative stage through a factory and includes racks for supporting shoes in a plurality of different positions and provided with a movable roller which may either engage a toe 10 of a last or the sole of the shoe adjacent the toe.

This invention will be best understood from a consideration of the following detailed description of the accompanying drawings; nevertheless, it is to be understood that the invention is not confined to the disclosure being susceptible of such changes and modifications as shall define no material departure from the salient features of the invention as 20 expressed in the appended claims.

In the drawings:—

Figure 1 is a side view of a rack constructed according to the principles of my invention,

Figure 2 is a vertical section of the rack,

Figure 3 is a top plan view of the same, showing a means for supporting lasts,

Figure 4 is a transverse vertical section taken along the line 4—4 of Fig. 2,

Figure 5 is a fragmentary view in perspective of the rack showing a method of supporting shoes,

Figure 6 is a fragmentary view in perspective of the rack showing another method of supporting shoes.

Referring more particularly to the drawings, 10 and 11 designate a pair of side panels or posts which are secured to a pair of base members 12 running longitudinally of the rack and connected together by a pair of transverse bars 13. Castors 14 of any approved type are secured to the longitudinal bars 12.

A plurality of shelves 20 are secured at their ends to the panels 10 and 11 and are supported by transverse bars 21 connected in any approved manner to the panels 10 and 11. A heel rest 22 is secured to the rear edges of the shelves and having their inner edges in abutting relation with the rear edges of the panels. Each shelf is cut away to form a slot 23 which is widened at 24 to receive the upper 25 of a shoe 26, thereby providing a restricted entrance between the section 27 of the shelf for the insertion of the upper of the

shoe. The sections may be formed separately 55 and have their enlarged portions 28 in abutting relation, or the sections may be formed by providing the slots for the full width of a board. The shelves may also be formed of metal if desired. A flange 29 is secured to 60 the outer end of each shelf and to the panels 10 and 11 for aiding in maintaining the shoes or lasts in position.

A bar 30 constituting a rest for the instep of a sole of a shoe is secured to each shoulder 65 20 and in contacting relation with the heel rest 22. This bar is covered with a felt, as indicated at 31 in order to prevent any abrasion of the material.

A roller 40 is covered with felt, as indicated 70 at 41 and is rotatably mounted at its ends on the bars 42 which are pivotally connected at 43 to the opposite flanges 29 so that the roller may be placed in the position shown in Figs. 3 and 6 for aiding in retaining lasts 45 on the rack, or for supporting the toe of the shoe 26 when the uppers of the shoes are inserted 75 within the slots 23. It will be noted that all of the shelves 20 are inclined at a slight angle to the horizontal and that the shelves project 80 at their forward ends a considerable distance beyond the forward edges of the panels 10 and 11 to facilitate in the ready insertion or the positioning of the shoes or lasts on the rack.

I claim:—

1. A rack for shoes comprising a pair of vertically disposed panels, shelves secured to the panels in spaced relation and provided with a heel rest and a toe rest, means pivotally 90 mounting the toe rest whereby the rest may be located in a plurality of different positions on the shelves.

2. A rack for shoes comprising a pair of vertically disposed panels, shelves secured to the panels in spaced relation and provided with a heel rest and a toe rest, means pivotally mounting the toe rest whereby the rest may be located in a plurality of different positions, the shelves having longitudinal 100 slots to receive the uppers of the shoes.

3. A rack for shoes comprising a pair of vertically disposed panels, shelves secured to the panels in spaced relation and provided with a heel rest, a felt covered roller, arms pivotally connected adjacent the opposite ends of the shelves, the rollers being revolvably mounted in the free ends of the arms whereby 105

said roller may be located in a plurality of different positions for supporting the toes of the shoes.

4. A rack for shoes comprising a pair of vertically disposed panels, shelves secured to the panels in spaced relation and provided with a heel rest, a felt covered roller, arms pivotally connected adjacent the opposite

ends of the shelves, the rollers being revolvably mounted in the free ends of the arms whereby said roller may be located in a plurality of different positions for supporting the toes of the shoes, a covered bar secured to each shelf adjacent the heel rest. 10

CHARLES E. SHIVELY.
